DOOR CLOSER

Giuseppe L. Cerami, Brooklyn, N. Y., assignor to
Cerami Self-Closing Device Corporation, New
York, N. Y.

Application January 16, 1936, Serial No. 59,465

19 Claims.

(Cl. 16—80)

This invention relates to spring means for holding hinged doors normally closed and for urging them to closed position when open. The invention further relates to spring hinges of the general type shown and described in my prior application for patent for spring hinge, filed July 5, 1935 and bearing the Serial No. 29,985.

One important object of this invention is to simplify the construction of my aforesaid prior application so as to effectively accomplish the desired result with a considerably less number of parts.

A second important object of the invention is to so arrange the parts that they may be assembled and disassembled with great ease in making repairs and lubrication of the device.

A third important object of the invention is to simplify the different parts of the invention so that they may be readily machined as by automatic or semi-automatic machine tools thus providing for low cost production.

A fourth important object of the invention is to provide a novel device of this sort which may be applied to a hinge supported door while not in itself constituting a hinge.

A fifth important object of the invention is to provide novel means whereby the tension of the springs used in the device may be adjusted.

A sixth important object of the invention is to provide novel means, in connection with such a device, whereby the door may be latched in open position against accidental closing.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a horizontal section through a portion of a door and its frame and showing one form of the device in position, the latter being shown partly in section.

Fig. 2 is a vertical section through such door and frame likewise showing such device partly in section and partly in elevation.

Fig. 3 is a perspective view of this form of the invention removed from the door and frame and having its casing also removed.

Fig. 4 is a detail section on the line 4—4 of Fig. 3.

Fig. 5 is a small scale section through a door

and frame with the door partly open and the device installed.

Fig. 6 is a plan view of a second form of the invention with those parts of a door and frame to which it is attached indicated in dotted lines.

Fig. 7 is a perspective view of a pair of hinge leaves adapted to constitute parts of this second form.

Fig. 8 is a section on the line 8—8 of Fig. 6, certain parts being left in elevation.

Fig. 9 is a section on the line 9—9 of Fig. 8.

Fig. 10 is a rear elevation of this form of the invention.

Fig. 11 is a section on the line 11—11 of Fig. 8.

Fig. 12 is a perspective view showing a means for attaching the device to the edge of a door between the door hinges.

Fig. 13 is a section similar to Fig. 9 but showing the attaching means of Fig. 12.

In the forms of the invention here shown the door is indicated at D and the part of the frame carrying the door hinges at F, the latter being provided with a pocket P wherein the main part or body of the invention is seated.

In the forms of the invention shown in Figs. 1 to 5 the body of the device comprises a front plate 10 from the rear face of which extends side walls 11 and top and bottom walls 12, these walls forming a rectangular casing open at its rear end and opening at its front end through the plate 10.

Slidable in this casing is a plunger 13 vertically reduced at its forward end to form a hinge eye 13'. Extending from the rear end of this plunger is a pair of vertically spaced parallel bores 14 and slots 15. Said slots extend from the rear ends of these bores 14 through the top and bottom faces of said plunger 13. Seated in the bores 14 is a pair of strong coiled compression springs 16 which have their rear ends connected by a seat plate 17. Across the slots 15 extend pivot pins 18 whereon are pivoted levers 19 each having a short arm bearing against the rear face of the plate 17 and a long arm bearing against the rear of a roller 20 journalled in a slot 21 at the rear of a plate or wall 12.

In connection with this part of the device there is provided a door plate 23 having vertically spaced hinge eyes 24 between which fits the hinge eye 13', a pin 25 passing through the eyes and thus pivotally connecting the door plate with the parts supported by the door frame, that is, the body of the device.

The plunger is provided opposite one of the hinge eyes with a slot 26 registering with a slot 27 in one side of the casing. A bell crank lever 55

28 is pivoted in the slot 26 and has an arm extending in the slot 27 but normally held out of contact with the adjacent eye 24 by a light spring 29. This lever is provided with a lug 30 which 5 may be moved by a user to engage in a notch 31 when the door is fully open. Obviously there may be several of such notches to hold the door in any desired open position.

In operation as the door is opened as shown in 10 Fig. 5, the plunger will be pulled out. This moves the pivots 18 forwardly and causes the levers 19, by engagement with the fixedly positioned rollers, to tilt so that their short ends move forwardly relative to the plunger and thus compress 15 the springs 16. Obviously, when the door is released these springs will act to restore the levers to normal position and draw the plunger rearwardly thus closing the door.

In the form of the invention shown in Figs. 6 20 to 13 there are also a body portion and a door portion. This body portion includes a face plate 32 projecting rearwardly from which is a casing having a central rectangular portion 33 open at its rear end and open at its front end through 25 the face plate 32. Bores 34 are formed in this casing above and below the central portion 33. Bores 35 extend vertically through the bores 34 and open into the central part 33 in alignment with each other. Slidably in the bores 35 are 30 pistons 36 bifurcated at their inner ends and these pistons are provided on their rear faces with bevelled cam notches 37. In the notches 37 engage forwardly extending lips 38 formed on forward spring seats 39. Bolts 40 extend rotatably through the face plate 32 centrally of the longitudinal bores 34 and pass through the bifurcations of the pistons and slidably through the spring seats. On the rear ends of these bolts are nuts 41 and between the front and rear 40 spring seats are coiled compression springs 42 the tension and compression of which may be adjusted by rotation of the bolts 40. These springs act to force the pistons 36 inwardly by engagement with the bevels of the notches 37.

45 Slidable in the casing 33 is a plunger 43 having inclined channels 44 in its upper and lower edges, these channels increasing in depth from rear to front so that a wedge like portion is left between said channels. Rollers 45 are journaled in the 50 bifurcated ends of the pistons and engage the bottoms of these channels so that, as the pistons are forced towards each other the plunger will be forced rearwardly. Obviously, the inclination of the bevelled faces of the pistons and the 55 inclination of the channels will be such as to accomplish this result. Also, whatever inclination is used the forward movement of the plunger 43 will be spring resisted.

In the forward end of the plunger 43 is a 60 transverse slot 46 at the rear end of which is pivoted a link 47 which projects forwardly of the plunger 43 and is provided at its forward end with a hinge eye 48.

The door supported part of this device may 65 constitute one leaf 49 of a hinge having a leaf 50 for attachment to the face plate 32 and provided with an opening 51 through which the plunger 43 may pass. In this form the leaf 49 has a pair of hinge ears 52 between which the 70 forward end of the link 47 is pivoted. Otherwise it may consist of a plain plate 53 having a pair of hinge ears 54 between which the forward end of the link 47 is pivoted.

In either case as the door is opened the plunger 75 43 is pulled forward and the pistons are wedged

apart thus forcing the forward spring seats rearwardly and compressing the springs.

There has thus been provided a simple and efficient device of the kind described and for the purpose specified.

It is obvious that minor changes may be made in the form and construction of the invention without departing from the material and spirit thereof. It is not, therefore, desired to confine the invention to the exact form herein shown 10 and described, but it is desired to include all such as properly come within the scope claimed.

Having thus described the invention, what is claimed as new, is:

1. In a device for the purpose described, a 15 face plate, a casing carried by the face plate and opening therethrough, a plunger slidable in said casing to move in and out through said face plate, said casing and plunger constituting a pair of telescopic members, one of said members being provided with a pair of longitudinal bores, a horizontally disposed compression spring in each bore, each of said springs having one end supported in the bore against longitudinal movement and adapted for coactal cooperative movement, a door plate movable toward and from the face plate, an operative connection connecting the plunger and door plate, and means engaging the free ends of the springs actuated by forward movement of said plunger for synchronously compressing the springs in a single direction.

2. In a device for the purpose described, a face plate, a casing carried by the face plate and opening therethrough, a plunger slidable in said casing to move in and out through said casing, 35 said plunger having a pair of longitudinal bores closed at their forward ends, coiled compression springs held in said bores and resting against the closed forward ends, and spring compressing means engaging the rear ends of said springs 40 and operable to compress the springs upon forward movement of the plunger in the casing.

3. In a device for the purpose described, a 45 face plate, a casing carried by the face plate and opening therethrough, a plunger slidable in said casing to move in and out through said casing, said plunger having a pair of longitudinal bores closed at their forward ends, coiled compression springs held in said bores and resting against the closed forward ends, a seat plate at the rear ends 50 of said springs, levers pivoted intermediate their ends to the plunger at the rear thereof and each having one arm pressing against the rear face of the seat plate, and rollers journaled in fixed 55 positions on the rear part of the casing and engaging the forward faces of the remaining arms of said levers.

4. In a device for the purpose described, a face plate, a casing carried by the face plate and opening therethrough, a plunger slidable in said casing to move in and out through said casing, said plunger having a pair of longitudinal bores closed at their forward ends, coiled compression springs held in said bores and resting against the closed forward ends, spring compressing means engaging the rear ends of said springs and operable to compress the springs upon forward movement of the plunger in the casing, and a door plate normally resting against the forward face of the face plate and hingedly connected to the forward 70 end of said plunger.

5. In a device for the purpose described, a face plate, a casing carried by the face plate and opening therethrough, a plunger slidable in said casing to move in and out through said casing, said 75

plunger having a pair of longitudinal bores closed at their forward ends, coiled compression springs held in said bores and resting against the closed forward ends, a seat plate at the rear ends of 5 said springs, levers pivoted intermediate their ends to the plunger at the rear thereof and each having one arm pressing against the rear face of the seat plate, rollers journalled in fixed positions on the rear part of the casing and engaging 10 the forward faces of the remaining arms of said levers, and a door plate normally resting against the forward face of the face plate and hingedly connected to the forward end of said plunger.

6. In a device for the purpose described, a face 15 plate, a casing carried by the face plate and opening therethrough, a plunger slidable in said casing to move in and out through said casing, said plunger having a pair of longitudinal bores closed at their forward ends, coiled compression springs 20 held in said bores and resting against the closed forward ends, spring compressing means engaging the rear ends of said springs and operable to compress the springs upon forward movement of the plunger in the casing, a door plate normally resting 25 against the forward face of the face plate and hingedly connected to the forward end of said plunger, and cooperating latch means on said plunger and door plate to hold the door plate in desired angular relation.

30 7. In a device for the purpose described, a face plate, a casing carried by the face plate and opening therethrough, a plunger slidable in said casing to move in and out through said casing, said plunger having a pair of longitudinal bores closed 35 at their forward ends, coiled compression springs held in said bores and resting against the closed forward ends, a seat plate at the rear ends of said springs, levers pivoted intermediate their ends to the plunger at the rear thereof and each 40 having one arm pressing against the rear face of the seat plate, rollers journalled in fixed positions on the rear part of the casing and engaging the forward faces of the remaining arms of said levers, a door plate normally resting against the 45 forward face of the face plate and hingedly connected to the forward end of said plunger, and cooperating latch means on said plunger and door plate to hold the door plate in desired angular relation.

50 8. In a device of the kind described, a face plate, a casing carried by and opening through said face plate, said casing having longitudinal bores respectively at the top and bottom edges thereof, said casing further having aligned vertical bores leading out through said upper and lower parts and intersecting said first bores, a plunger movable in the casing between the bores and having its upper and lower sides inclined to form a central wedge portion arranged with its 55 larger end at the rear, pistons movable through the vertical bores and supported on the inclined sides of the wedge portion, said pistons being provided with cam faces, spring seats in said longitudinal bores engaging said cam faces, 60 springs extending in the longitudinal bores and each having an end engaging a spring seat, and spring seats supporting the remaining ends of the springs against movement.

9. In a device of the kind described, a face 70 plate, an open casing carried by and opening through said face plate, said casing having longitudinal bores respectively at the top and bottom edges thereof, said casing further having aligned vertical bores leading out through said upper 75 and lower parts and intersecting said first bores,

a plunger movable in the casing between the bores and having its upper and lower sides inclined to form a central wedge portion arranged with its larger end at the rear, pistons movable through the vertical bores and supported on the inclined sides of the wedge portion, said pistons being provided with cam faces, spring seats in said longitudinal bores engaging said cam faces, 10 springs extending in the longitudinal bores and each having an end engaging a spring seat, spring seats supporting the remaining ends of the springs against movement, and means to adjust the positions of the last mentioned spring seats.

10. In a device of the kind described, a face 15 plate, a casing carried by and opening through said face plate, said casing having longitudinal bores respectively at the top and bottom edges thereof, said casing further having aligned vertical bores leading out through said upper and lower parts and intersecting said first bores, a 20 plunger movable in the casing between the bores and having its upper and lower sides inclined to form a central wedge portion arranged with its larger end at the rear, pistons movable through the vertical bores and supported on the inclined 25 sides of the wedge portion, said longitudinal bores guiding said cam faces, springs extending in the longitudinal bores and each having an end engaging a spring seat, spring seats supporting the remaining ends of the springs against movement, 30 means to adjust the positions of the last mentioned spring seats, a door plate normally resting against said face plate, and a link pivotally connected to said door plate and plunger.

11. A device for automatically closing doors, 35 comprising a face plate, a casing carried by the face plate and movable therewith, reciprocable means in the casing adapted to extend thru the face plate and being telescopic therewith, a plurality of spaced, parallel compression members 40 movable in said reciprocable means, each of the members having one end supported in the casing, a door plate connecting the face plate and relatively movable therewith, operable means interconnecting the door plate and the reciprocable 45 means, and actuatable means for engaging the free ends of the compression members upon movement of the reciprocable means whereby the members are simultaneously compressed to return the reciprocable member to normal position.

12. The combination with a door plate, of a face plate having a casing, opening therewith, reciprocable means connecting the door plate and movable in and out of the casing, a plurality of 55 spaced compression members in the reciprocable means, supporting means abutting one end of the compression members, a pair of opposed levers pivoted intermediate their ends to the plunger for pressing against the supporting means on 60 movement of the plunger, and opposed rollers journalled to the casing for slidably contacting the levers.

13. The combination according to claim 12, 65 in which cooperative latching means are mounted on the plunger to engage the door plate to hold the same in desired stationary position.

14. A closing device for doors and the like, comprising a door plate, a casing having a face plate normally abutting the door plate, a plunger reciprocable in the casing and connected with the door plate, a plurality of spaced parallel compression members mounted in the casing and actuatable by said plunger, upon movement of the door plate, and pivoted contacting means in the 70 75

casing abutting one end of the compression members for normally returning the plunger to its position in the casing.

15. A device according to claim 14, in which the plunger is provided with tensioned latching means for engaging the door plate and retaining the same in desired angular relation.

16. A device for automatically closing doors, comprising a face plate, a casing connected with the face plate and opening therethru, plunging reciprocable means in said casing and forming a telescopic member therewith, one of said members being provided with a pair of longitudinal bores, coacting, cooperative horizontal compression members for the bores, being supported at one end thereof against longitudinal movement, a door plate pivotally connected with the plunging means, and means in connection with the free ends of the spring actuatable by the forward movement of the plunger for horizontally compressing the springs in a single direction counter to the action of a door when being swung open.

17. A door closing device, comprising a cas-

ing, a reciprocable plunger in the casing, a plate member hingedly connected with the plunger, and spaced horizontal spring members in the casing in cooperative connection with the plunger adapted upon compression of the springs to retract the plunger into the casing.

18. A closing device for doors and the like, comprising a casing, a plunger reciprocable in and out of the casing, a door plate in hinged connection with the plunger, a plurality of spaced, parallel compression members adapted to coact on reciprocation of the plunger, disposed on either side of the plunger in the casing, and a plurality of coacting means interconnecting the members and the plunger for normally drawing the same into rest position.

19. A closing device according to claim 18 in which the plunger is provided with means for engaging the door plate and retain the same in fixed position against the action of the compression members.

GIUSEPPE L. CERAMI.
